UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

CASTING-MACHINE FOR ELEMENTS OF PRINTING-FORMS.

1,220,059.

Specification of Letters Patent. Patented Mar. 20, 1917.

Application filed July 20, 1916. Serial No. 110,360.

To all whom it may concern:

Be it known that we, JOHN SELLERS BANCROFT and MAURITZ C. INDAHL, citizens of the United States, residing at Philadelphia, 5 in the county of Philadelphia and State of Pennsylvania, have invented certain new and useful Improvements in Casting-Machines for Elements of Printing-Forms; and we do hereby declare the following to be a full, 10 clear, and exact description of the same, reference being had to the accompanying drawings forming part of this specification.

One of the modern developments in the type casting machine art has been a machine 15 or an attachment for a machine whereby strips of type metal may be cast in succeeding increments fused together, such strips being adapted to form leads, rules, tie-up strips, etc., and while it has been found 20 practical and the machine has gone into extensive public use for the production of elements for the printing form, where the edge of the strip does not form a printing surface as well as where the edge of the strip 25 is a simple continuous printing edge, or series of printing edges, difficulty has been encountered in providing a machine which will form a strip of the character mentioned 30 having an ornamental, discontinuous or varied printing surface.

It is one of the objects of the present invention to provide an apparatus adapted for the production of rules or borders having a printed surface of any desired character 35 and to provide means whereby the character of the printing surface may be changed at will, or in accordance with a predetermined design during the operation of the machine, thus permitting of the production 40 of rules or borders having a multiplicity of design characteristics, especially designs which are composed of parts periodically repeated in a certain order or sequence. Other objects of the invention are to provide im- 45 proved and simplified mechanism, whereby the resultant strips are made more uniform and accurate and their production a matter of automatic machine work requiring but little or no attention on the part of the op- 50 erator.

The invention has been developed in its

practical embodiment as a part of the well known type casting machine, manufactured and marketed by the Lanston Monotype Machine Co., and is illustrated in the accompanying drawing in connection with a machine of that type, many of the parts of the machine however being omitted where such parts do not perform a function in direct association with the parts constituting the present invention, and other parts, although performing no such function, are shown in order that the relation of the invention to the whole machine may be readily comprehended. 65

Referring to the said drawings,—

Figure 1 is a top plan view of a casting machine such as specified, with the present improvements incorporated therein.

Fig. 2 is a view looking at a portion of 70 the front of the machine, or from a point of view to the right of Fig. 1, this view being on an enlarged scale.

Fig. 3 is a view corresponding to Fig. 2, but showing another portion of the machine. 75

Fig. 4 is a perspective view showing the cross heads for the matrix clamping mechanism and centering pin.

Fig. 5 is a sectional view with parts 80 broken away showing the arrangement of a series of matrices mounted to move transversely of the mold cavity.

Fig. 6 is a sectional view in a vertical plane substantially at right angles to the 85 plane of the section of Fig. 5.

Fig. 7 is a detail perspective view showing the knife for trimming off the metal which discharges through the vent opening and the friction clamp or brake for 90 holding the strip in the position to which it is moved by the feeding mechanism.

Fig. 8 is a sectional view through the parts shown in Fig. 7.

Fig. 9 is a sectional elevation showing the 95 construction of the operating plunger for the centering pin and matrix clamping mechanism.

Fig. 10 is a transverse section in a plane indicated by the line 10—10, Fig. 9. 100

Figs. 11 and 12 are views of short sections of borders such as have been produced

with this apparatus, these views being on an enlarged scale, inasmuch as the actual size of the rules will correspond in width to the height of ordinary printing type and in thickness to the desired point size.

5 Fig. 13 is a perspective view of the matrix carrier having a series of matrices therein, the carrier and matrices being in inverted position.

10 Like reference characters in the several figures indicate the same parts.

In the adaptation of the casting machine for casting leads and rules now in general use and which is set forth in a preferred embodiment in an application for patent filed by Amos L. Knight, Serial No. 864,894, filed October 3, 1914, the successive increments which go to form the strip are cast in a mold, one wall of which is formed by a mold blade and another wall of which is formed by the metal previously congealed in the mold. Generally speaking, the mold blade operates at substantially right angles to the line of operation of the mold blade in the ordinary type caster; in other words, it is located substantially in the position ordinarily occupied by the movable cross block. The strip is ejected or fed forwardly by the advance of the mold blade, the mold blade 25 retreats, a new charge of metal is injected into the mold, congeals therein and uniting to the previously congealed portion and is in turn advanced or fed forwardly by the next movement of the mold blade. These operations are well understood and need no further description herein, save that in the present mechanism provision is made for slowing down the movement of the mold blade which latter derives its motion from the lever which ordinarily operates the cross block. For slowing down this motion, the lever which ordinarily operates the cross block and which is indicated at 246 in Fig. 3 of the drawing is at its upper end connected by link 247 with the lower end of a lever 248 pivoted to a fixed part of the machine and at its upper end connected with the casing 249 of a spring box of well known construction.

50 The plunger or inner member 250 of the spring box is connected with the upper end of another lever 251, also pivoted to a fixed part of the machine frame and at its lower end jointed to the rear end of the connecting rod 35 which extends forwardly and is jointed to the mold blade 27.

As it will be seen in Figs. 2 and 6, the mold blade is adapted to reciprocate in a mold 28, the construction of which it is not necessary to describe in detail herein, further than to say that it embodies a base, side blocks 33 and 34 between which the mold blade reciprocates, and is open on two sides; that is to say, at the side opposite the front edge of the mold blade and at the top, where

it is adapted to be closed by the matrix to be hereinafter described. The metal is retained in the exit opening by extending the walls of the mold forwardly or in the direction of feed of metal strip, and in addition, 70 friction means are provided for imposing a certain degree of resistance to the forward movement of the strip and for retaining the strip in the position to which it may be fed.

The friction device or brake, as it may be 75 called, is illustrated in detail in Figs. 7 and 8, and by reference to these figures it will be seen that the metal strip issuing from the mold passes between the inner face of the diagonally arranged knife 29 and the outer 80 face of the spring pressed clamp 30. The clamp 30 is suitably guided in the mold base and is advanced by a spring 31. Its advance movement is limited by an adjustable stop or set screw 32, and in operation it 85 serves to press the metal strip against the inner face of the knife, thereby performing a double function; that is to say, it serves to retain the strip in position against accidental longitudinal displacement and it 90 serves to hold the side of the strip against the face of the knife so that the metal which ordinarily escapes through the air vent passage in the mold will be cleanly severed and the side of the strip left perfectly smooth. 95

Metal is injected by means of the ordinary metal pump mechanism through a nozzle at the bottom of the mold cavity, as shown in Figs. 5 and 6, but previous to the injection of metal a matrix is clamped down on top 100 of the mold in position to form the top wall of the cavity. This matrix overlaps the mold blade and a portion of the metal which was previously congealed in the mold cavity but which has been advanced or fed forward 105 by the mold blade.

In accordance with the present invention, the matrix is adapted to be moved toward and from the mold in order to accomplish two important results. By raising and lowering the matrix it becomes possible to form a printing surface on the edge of the strip which is composed of recurrent patterns and either continuous or discontinuous, for during the casting operation the matrix will be 115 clamped in position and during the feeding of the strip the matrix will be lifted so that the strip may be fed forward without interference and without injury to the printing surface. Furthermore, should it be desired 120 to cast strips with various designs for the printing surface this may be accomplished by providing for the use of a series of matrices any one of which may be brought into position for being clamped to the top of the 125 mold during the casting operation, and by the provision of a number of different matrices the pattern of the printing surface may be varied almost indefinitely, as each matrix may be cut to form a portion only of the de- 130

sign to be embodied in the complete printing surface. Examples of border designs are shown in Figs. 11 and 12.

To support the matrices and bring them into proper position for coöperation with the mold they are mounted in a carrier 40 which is conveniently supported in guideways 41 attached to or formed on the under side of a head 42. The head 42 is supported from a bridge 43 which substantially corresponds to the bridge employed on the type casting machines before referred to. The said bridge is provided with sleeve bearings 44 through which rods 45 extend from the head 42 to a cross head 46. Interposed springs 47 surrounding the sleeve bearings serve to hold the cross head and matrix carrier head with the matrix carrier elevated and to permit of the same being periodically depressed to bring the desired matrix into proper relation with the mold for casting.

The matrices 48 in some respects may resemble the matrices used in type casting, that is to say, they have the desired cavity or cavities in their lower faces and in their upper faces they are provided with conical cavities 49 for the reception of the centering pin 50, and they are preferably mounted in the carrier by means which will permit of their being accurately centered, and at the same time readily changed should it be desired to change the pattern of the printing surface on the strip. Conveniently, each matrix is mounted in its own cavity or cell in the matrix carrier and the whole series of matrices is held in place by a pair of pins 51 projecting from a head 52 and adapted to extend through registering openings in the matrices and walls of the cells, as will be readily understood from an inspection of Figs. 6 and 13. The retaining pins are held in place against accidental release by an ordinary spring retainer 53 (Fig. 13) secured to the carrier. The centering pin 50 is guided in a centering pin chuck 54 of standard construction, and at its upper end is connected with a cross head 55 connected by loose rods 56 with an upper cross head 57 (Fig. 4). Interposed springs 58 on the rods 56 serve to depress the centering pin when the upper cross head 57 is moved downwardly, and for the purpose of periodically moving the cross heads 57 of the centering pin and 46 of the matrix head 55 downwardly the cross head 57 is provided with a central plunger 59, adjustably associated therewith through an adjusting nut 60, and at its lower end this plunger 59 is provided with a head 61 upon which the forward end of the usual centering pin actuating lever 61 is adapted to exert a downward pressure whenever said lever is moved in the proper direction by means of the usual operating cams on the power shafts 65 of the machine. This lever 61 and its ac-

tuating mechanism are of standard construction and need not be further described, as they are well understood by those skilled in the art.

The plunger 59 (Fig. 9) passes through the cross head 46 and is surrounded by a sleeve 62 having at its upper end adjusting nuts 63 and an internal shoulder 64 for coöperation with a shoulder on the plunger for limiting the relative movement of the plunger and sleeve. A spring 65 surrounding the plunger intermediate the cross head 57 and sleeve serves to depress the latter when the plunger is depressed, and by the engagement of the lock nuts 63 with the cross head 46 the latter, together with the matrix carrier head will be depressed, there being a proper range of independent movement by reason of the sleeve 62 sliding in the cross head 46 to permit of the adjustment of the parts in such wise that the centering pin may be brought to its seat at the proper time for centering the matrix, preliminary to the final clamping action on the upper face of the mold.

The lower end of the sleeve 62 is cut away on opposite sides so as to form depending fingers 66 and provision is made for adjusting the sleeve angularly about the plunger and holding it in such adjusted position by means of a spring pressed pin 67 (Fig. 10), whereby, when desired, the end of the operating lever 61 may be caused to engage said fingers and so elevate the centering pin, or when the sleeve is turned to the other position, the said lever 61 may move upwardly leaving the centering pin within its centering cavity in the matrix. The latter operation is desirable under circumstances where the same matrix is to be used for the making of a large number of casts, but where the matrix is to be shifted or new matrices brought into position, the centering pin must be withdrawn from said centering cavity to permit of the necessary movement.

To insure the lifting of the cross head 46 and matrix head 42, together with the matrix carrier under all circumstances, an adjustable stop or shoulder in the form of a set screw 68 is provided on the said cross head 46 in position to coöperate with the top of the lever 61, as the latter reaches the upper extreme of its movement. Thus, should the fingers 66 be out of position to coöperate with the lever 61 and the matrix head and carrier stick for any reason, the movement of the operating lever 61 will insure the lifting of the matrix before the advance of the mold blade and feeding of the strip takes place.

Obviously, when printing surfaces are being formed, the pattern of which embodies matching parts of a design, the several parts being in different matrices, extreme accuracy

is necessary in order that a proper mating of the edges will occur so as to leave no blemish in the print. For this reason it is important that accurate means shall be provided for gaging the movement of the mold blade. In the preferred construction the mold blade is advanced to a definite point which may be determined by any suitable fixed stop or by the forward throw of the actuating mechanism, but the return movement is regulated by a stop mechanism having a micrometer adjustment, whereby the length of each cast increment of the strip may be regulated with the greatest accuracy. This stop mechanism is illustrated in Fig. 2 of the drawings, by reference to which figure it will be seen that a tapering or wedge-shaped abutment 70 is located in position to form a stop for the rear end of the mold blade 27. The wedge or stop abutment is mounted in an inclined position whereby its stop face will be vertical and its adjustment is effected by a micrometer screw 71 controlled by the milled end 72, which latter is held in adjusted position by a spring detent 73. With this arrangement the direct adjustment by the micrometer screw is effected through the wedge or tapering surfaces of the stop in acting upon the mold blade and consequently the adjustment may be made with the utmost accuracy and with the finest fractional measurement, so that it becomes entirely practical to adjust the mold blade to secure the absolute matching or mating of different portions of a pattern which it is desired to have incorporated in the printing surface of the strip.

The machine is designed to perform its functions of casting succeeding increments of the strip automatically, and it is, therefore, necessary to provide means for automatically shifting the matrices when the pattern of a printing surface is to be composed of designs, portions of which are found in the different matrices. The well known machine for casting type to which the embodiment of the invention illustrated is applied embodies means for shifting a matrix carrier or die case from one position to another under the control or direction of a record strip or ribbon. The ordinary mechanism found in the machine for shifting the matrix carrier or die case in one direction is utilized for shifting the matrix carrier of the present invention. Referring particularly to Figs. 1 and 5 it will be seen that the matrix carrier 40 is connected by a hook or coupling 74 with the usual cross head or cross slide 75 for giving motion to the die case or carrier in the ordinary machine. This cross slide 75 is moved back and forth to bring the proper matrix into position over the mold by the usual and well known means embodying the sets of tongs 76 and 77, the pin jaws 78, and air pins 79 which are adapt-

ed to be blown up to form stops for the pin jaws. The air pins are blown up or projected under the control of a paper record strip in the paper tower 80, as usual, and in the formation of the perforations in the record strip they are so positioned that the proper pins will be projected for arresting the pin jaws so as to control the movement of the matrix carrier to the proper point for positioning the desired matrix over the mold.

The centering pin lever 61, besides centering the matrix and clamping the same down on top of the mold, is adapted to perform an additional function in that it exerts a pressure or clamping action through suitable mechanism on one of the blocks forming the side of the mold itself. This action is desirable inasmuch as the mold pressure should be reduced slightly during the actual feeding of the strip, and this is best accomplished by relieving the pressure on one side of the mold. In the preferred construction best seen in Figs. 1, 2 and 5, the mold base 28 is provided with a clamping screw 80^a which clamping screw passes through a nut 81 mounted in the mold base, the end of the screw being adapted to bear against the outside of the block 34. As a convenient detail of construction the nut 81 is provided with a square head 82 located in the mold base, and the body of the nut projects through an opening in said base. The outer end of the screw is provided with an adjustable arm 83 (Fig. 2) to the end of which is jointed a connecting rod 84 extending upwardly and through the end of a supplemental lever 85 carried by the centering pin lever 61. Surrounding the connecting rod 84 is a coil spring 86 through which the downward pressure of the operating lever is transmitted to the arm 83 and screw 80^a. As a result of this arrangement, at the time when the matrix is centered and clamped the screw 80^a is also turned in a direction to exert a pressure on the side block 34 and when the matrix is lifted preliminary to the forward movement of the mold blade, such pressure is relieved and the strip may feed forwardly without danger of deformation and without material frictional resistance in the mold itself.

In connection with the feed movement of the strip it may be remarked that it is quite important that the strip should be held down or prevented from rising at the rear end, and practice has demonstrated that this result can best be accomplished by forming the mold blade with a shoulder or overhang preferably located near the upper edge. This overhang is indicated at 87 in Fig. 6 on a somewhat exaggerated scale, inasmuch as practice has shown that an overhang of five-thousandths of an inch is sufficient to accomplish the desired end.

In operation, the molten metal is injected at the bottom of the mold cavity by the

usual pump mechanism and after the injected metal has congealed, the matrix is lifted and the mold blade advances, pushing the congealed metal in front of it. When 5 the mold blade again recedes, it leaves an open space constituting the mold cavity, and preliminary to the next casting operation, the proper matrix is centered over the mold and clamped in position, whereupon more 10 molten metal is injected and the operations are repeated the number of times necessary for the production of a strip of the desired length. The strip is usually one of indeterminate length which is subsequently severed 15 by suitable shearing mechanism and with the present arrangement the pattern of the printing surface may be varied at will under the control of the record strip or ribbon by the shifting of the matrix carrier so as to bring one or the other of the matrices 20 into position for coöperating with the mold.

It is, of course, necessary that each matrix should overlap to some extent the congealed section of the metal forming one 25 wall of the mold cavity as well as the forward end of the mold blade itself, inasmuch as such overlapping forms the most convenient and certain means for making a tight joint at these points and insuring the proper 30 mating of the upper edge surfaces of the several sections which together form the completed strip.

What is claimed is:

1. An apparatus for casting type metal 35 elements for printing forms, embodying means for confining a body of molten metal in contact with a surface of a previously congealed portion of the element being cast whereby the two portions are caused to unite 40 by fusion, means for intermittently advancing the element as succeeding increments congeal, means for feeding molten metal and means for forming a printing surface on the element comprising a matrix, 45 and means for periodically lifting said matrix during the advance movements of the element.

2. An apparatus for casting type metal 50 elements for printing forms embodying a mold having a cavity open on two sides, means for holding congealed metal in position to close one side of the cavity, a movable matrix for closing the other side of the cavity, means for lifting the matrix away 55 from the congealed metal, means for advancing the congealed metal while the matrix is lifted, and means for supplying molten metal to the cavity.

3. An apparatus for casting type metal 60 elements for printing forms embodying a mold having a cavity open at two sides, means for holding congealed metal in position to close one side of the cavity, a movable matrix for closing the other side of the 65 cavity, means for feeding the congealed

metal, means for moving the matrix during feed movements, and means for supplying molten metal.

4. An apparatus for casting type metal elements for printing forms embodying a 70 mold having a cavity in which the metal congeals, said cavity being open at one side for the exit of the congealed metal and provided with an opening for the entrance of molten metal, means for retaining the congealed metal in position to close the exit opening during the casting operation, a matrix forming one wall of the mold cavity, means for periodically lifting said matrix away from the mold cavity, and means for advancing the element while the matrix is 75 lifted.

5. An apparatus for casting type metal elements for printing forms embodying a 80 mold having a cavity open on two sides, a matrix movable toward and from the mold for closing one of said sides, means for holding metal congealed in the cavity in position to close the other of said sides, means for intermittently moving the matrix 85 away from the mold, and for advancing the casting to form a space for a succeeding increment, and means for forcibly injecting molten metal into such space.

6. An apparatus for casting type metal 90 elements for printing forms embodying a mold having a cavity open on two sides, means for holding metal congealed in the cavity in position to close one of said sides, means for advancing the congealed metal 100 to form a space in rear thereof, a matrix carrier movable transversely of the cavity, and a series of matrices mounted in said carrier and movable therewith into position to close the other of said open sides of the 105 cavity.

7. An apparatus for casting type metal elements for printing forms embodying a mold having a cavity open at two sides, means for supplying molten metal to the 110 cavity, means for advancing the metal when congealed out through one open side of the cavity and for holding the congealed metal in position to close said side, and a matrix 115 movable toward and from the mold and having an extension overlapping the congealed metal when the latter is advanced into position to close the side of the cavity.

8. An apparatus for casting type metal elements for printing forms embodying a 120 mold having a cavity open at two sides, means for supplying molten metal to the cavity, means for advancing the metal when congealed out through one open side of the cavity and for holding the congealed metal 125 in position to close said side, a matrix holder movable transversely of and toward and from the mold, a series of matrices mounted in said holder, and an extension on each matrix overlapping the congealed metal 130

when the latter is advanced into position to close the side of the cavity.

9. An apparatus for casting type metal elements for printing forms embodying a mold having a cavity for the reception of molten metal, a reciprocatory mold blade working in said cavity for feeding the congealed metal out of the cavity, means for holding the congealed metal in the exit opening to form one wall of the cavity, a matrix movable toward and from the cavity and provided with an extension overlapping the congealed metal in the exit opening, means for alternately lifting the matrix and advancing the mold blade, and means for supplying molten metal to the cavity.

10. In apparatus for casting type metal strips composed of successively cast sections united by fusion, the combination with a mold having a cavity therein open on the exit side, a matrix carrier movable transversely of the mold, a plurality of matrices mounted in the carrier and movable toward and from the mold to form one wall of the cavity, a mold blade working in the cavity to discharge metal congealed therein means for retaining the congealed metal in the exit to form one wall of the cavity, an adjustable stop for the mold blade, means for supplying molten metal, and means for periodically operating the mold blade and matrices.

11. In apparatus for casting type metal strips composed of successively cast sections united by fusion and having a printing surface at one edge, the combination with a mold having a cavity therein open on the exit side, a matrix for forming the printing edges movable toward and from the mold, means for moving the matrix, a mold blade working in the mold, means for holding the congealed metal in the exit opening of the mold to form one wall of the mold cavity and a stop for limiting the rearward movement of the mold blade embodying a wedge and a micrometer screw for adjusting said wedge, whereby the position of the mold blade may be determined for insuring the mating of the printing surfaces of the several sections of the strip.

12. In a casting machine such as described, the combination with the matrix carrier head, bridge in which said head is mounted to move vertically, and a cross head connected with said matrix carrier head, of a plunger mounted in said cross head, a spring intermediate the plunger and cross head for depressing the cross head, a centering pin, yielding connections intermediate said cen-

tering pin and plunger, and means for periodically depressing the plunger for moving the matrix carrier head and centering pin downwardly.

13. In a casting machine of the type described, a matrix centering and clamping mechanism embodying an operating lever, a matrix carrier head, a cross head connected with the matrix carrier head, a sleeve bearing mounted to move in the cross head, a plunger mounted in the sleeve bearing, said plunger and sleeve bearing being provided with a head and fingers respectively for coöperation with the operating lever, means for adjusting the fingers on the sleeve bearing into and out of position to coöperate with said lever, a centering pin, and yielding connections intermediate the centering pin and plunger, substantially as described.

14. In a casting machine of the type described, a matrix centering and clamping mechanism embodying a matrix carrier head, a cross head connected therewith, a sleeve bearing mounted to move in said cross head and having downwardly extending fingers thereon, a plunger mounted to move in said sleeve bearing and having a head thereon for coöperation with an operating lever, means for turning the sleeve bearing to move the fingers into and out of position for coöperation with an operating lever, a centering pin, yielding connections intermediate the centering pin and plunger, and yielding connections intermediate the plunger and sleeve bearing, whereby the centering pin and matrix carrier head will be advanced with a yielding pressure, one in advance of the other.

15. In a machine for casting type metal strips composed of successively cast sections united by fusion, the combination with a mold having a cavity therein open at the exit side, a mold blade working in said cavity toward and from the exit side for advancing the successive sections into position for closing the exit opening, and an operating lever for said mold blade, of connections intermediate said lever and mold blade embodying a pair of levers having unequal arms, one lever connected with the mold blade and the other with the operating lever, and a spring box intermediate the opposite ends of said pair of levers, whereby the movement of the mold blade will be slower than that of the operating lever.
